UNITED STATES PATENT OFFICE.

STACY B. HASELTINE, OF CHICAGO, ILLINOIS, ASSIGNOR TO WILLIAM H. MINER, OF CHICAGO, ILLINOIS.

MEANS OF CONNECTING DRAW-BAR TO DRAFT-YOKE IN RAILWAY DRAFT-RIGGING.

1,240,341.

Specification of Letters Patent. Patented Sept. 18, 1917.

Application filed September 13, 1912. Serial No. 720,153.

To all whom it may concern:

Be it known that I, STACY B. HASELTINE, a citizen of the United States, residing in Chicago, in the county of Cook and State of Illinois, have invented a certain new and useful Means of Connecting Draw-Bar to Draft-Yoke in Railway Draft-Rigging, of which the following is a full, clear, concise, and exact description, reference being had 10 to the accompanying drawings, forming a part of this specification.

My invention relates to improvements in the means of connecting the drawbar to the draft yoke in railway draft rigging.

15 The object of my invention is to provide a simple and efficient means of connecting the drawbar and draft yoke in railway draft rigging, and one in which the drawbar and draft yoke may be easily connected 20 and disconnected.

In the accompanying drawings forming a part of this specification, Figure 1 is a side elevation of the forward end of a draft yoke and the rear end of the drawbar embodying my invention. Fig. 2 is a plan view, partly in horizontal section on line 2, 2 of Fig. 1. Fig. 3 is a longitudinal, vertical section on line 3, 3 of Fig. 2. Fig. 4 is a cross-section on line 4, 4 of Fig. 1. Fig. 5 is 30 a perspective view of a block. Figs. 6 to 10 inclusive illustrate a modification; Fig. 6 being a side elevation, Fig. 7 a partial section on line 7—7 of Fig. 6, Fig. 8 a longitudinal vertical section on line 8—8 of Fig. 35 7, Fig. 9, a cross-section on line 9—9 of Fig. 6, and Fig. 10 a perspective view of a block.

Referring to the drawings, 11 represents the shank of a draw bar of usual construction, 12 the butt of the draw bar, 13 a draft 40 yoke, the forward portion of which is shown in drawing, 14 the upper strap and 15 the lower strap thereof. The draw bar is provided with the upper and lower transverse shoulders 16 and 17 respectively. The upper strap 14 of the yoke is forwardly provided with a downwardly turned gib 18, engaging the upper shoulder 16 of the draw bar. Substantially at a point in line with the rear face 19 of the butt of the draw bar, 45 the lower strap 15 of yoke 13 has a downward turn 20, in front of which the lower strap is forwardly extended in a plane substantially parallel with the opposite portion of the upper strap and a sufficient distance 50 therefrom to permit the butt of the draw bar

to clear the gib 18, in inserting it through the forward opening of the yoke. The upper and lower straps of the yoke are forwardly joined by the lateral webs or plates 21, 21, thus giving the yoke a head with the 60 box-like opening 22 formed between the webs and the yoke straps. The webs or plates 21, 21 are each provided near their lower portions with the L-shaped slot 23 to receive the transverse L-shaped block 24. 65 The block 24 has an upright member 25 and a flat member 26, having the shoulder 27 against which the lower shoulder 17 of the butt 12 of the draw-bar engages in normal position with the draft rigging. The block 70 24 extends at its ends beyond the outer edges of the plates 21, 21 and is provided with the perforations 28, 28 to receive the keys 29, 29 which hold it against accidental displacement. The top face 30 of the member 26 75 of the block 24, when within the slots 23, 23 is substantially even with the portion of the inner or upper face 31 of the lower yoke strap 13 back of the bend 20 therein. In the modification illustrated in Figs. 6 to 10 80 inclusive the draw-bar shank 32 and the butt thereof 33 are provided with the usual upper and lower transverse shoulders 34 and 35 respectively; the draft yoke 36, the forward end of which is shown in the drawing, has 85 an upper strap 37 and a lower strap 38; the upper strap 37 being provided with a downwardly turned gib 53 engaging the upper shoulder 34 of the draw-bar. The lower strap 38 is provided with the downward turn 90 or bend 39, in front of which it is forwardly extended in a plane parallel with the opposite portion of the upper strap and a sufficient distance therefrom to permit the butt of the draw-bar to clear the gib 38 in inserting the draw-bar through the forward opening of the yoke. The upper and lower straps of the yoke are forwardly joined by the lateral webs or plates 40, 40, thus providing a head for the yoke with the box-like opening 95 41 into which the draw-bar is received. The webs 40, 40 are transversely provided near their lower edges with the slot 42 to receive the transverse key 43, which passes there-through and through the transverse perforation 44 in the L-shaped block 45. The block 45 has an upright member 46 and a flat member 47, forming the shoulder 48, against which the lower shoulder 35 of the butt of the draw-bar engages in normal position 100 105 110

with the draft rigging. The top face 49 of the member 47 of the block 45, when in position, is substantially even with the inner portion or upper face 50 of the lower yoke 5 strap 38, back of the bend 39 therein. The key 43 is provided with the perforations 51, 51 at its ends to receive the cotters or pins 52, 52.

The operation of my device will be clear. 10 To remove the draw-bar, the block is withdrawn, permitting the butt of the draw-bar to be moved downwardly so that the upper shoulder thereof may clear the gib of the upper yoke strap and be forwardly withdrawn. To connect the draw-bar with the yoke, the butt of the draw-bar is inserted in the box-like opening of the member of the yoke, lifted to position so that the upper shoulder of the draw-bar engages the gib 15 in the upper strap of the yoke and then the block is secured in the lower portion of the said opening so that the shoulder thereon engages the lower shoulder of the draw-bar and the block is then secured in position in 20 the preferred form by inserting the pins in the ends thereof and in the modified form by passing the key therethrough. It will be seen that on the rearward movement of the draw-bar, the butt of the same will engage directly with the followers or compression resisting members within the yoke and without strain upon the yoke, that is, the draw bar is free to move rearwardly independently of the yoke, while on the forward 25 movement of the draw-bar the shoulders of the same will be in engagement with the shoulders provided on the upper strap of the yoke and upon the block.

I claim:

- 40 1. In a device of the class described, a draw bar having a butt forming oppositely disposed shoulders, a yoke forwardly provided with a laterally slotted box-like head to receive the draw bar, a shoulder within said head co-acting with one of the shoulders of the draw bar, a block passing through the slots in the yoke head having a shoulder co-acting with the other shoulder of the draw bar, said draw bar being free to move rearwardly independently of the yoke.
- 45 2. In a device of the class described, a yoke forwardly provided with a box-like opening, a draw bar provided with oppositely disposed shoulders and adapted to be received within said opening, a transverse shoulder within said opening adapted to engage one shoulder of the draw bar, and a removable block engaging the butt of the draw bar, said block being provided along its forward edge with an up-turned angular flange to engage the other shoulder of the draw bar, the draw bar being held within 50 the head by said shoulders and block, and

being free to move rearwardly therein independently of the yoke.

3. In a device of the class described, a draw bar provided with shoulders, a yoke provided with an upper and a lower strap, 70 the upper strap being forwardly provided with a transverse shoulder adapted to engage one of the shoulders of the draw bar and the lower strap having a depressed portion therein adapted to receive a block, a block, the latter being provided with a shoulder adapted to engage another shoulder of the draw bar, and means for securing said block in said depressed portion of the yoke, the draw bar being held in said head by said shoulders and being free to move rearwardly independently of the yoke.

4. In a device of the class described, a draw bar provided with shoulders, a yoke forwardly provided with a hollow box-like 85 head to receive the draw bar, a transverse shoulder within said head adapted to engage one shoulder of the draw bar, and a removable block provided with a shoulder adapted to engage the other shoulder of 90 said draw bar, the said head being provided with lateral slots to receive said block, the hollow portion of the yoke head extending below the plane of the inner lower face of the lower strap of the yoke, the said draw 95 bar being held within the yoke and free to move rearwardly therein independently of the yoke.

5. In a draft rigging for railway cars, a draw bar having oppositely disposed shoulders, a yoke forwardly provided with a laterally slotted hollow head to receive the draw bar, a shoulder within said head co-acting with one of the shoulders of the draw bar, a block passing through the slots in 100 the yoke head having a shoulder co-acting with the other shoulder of the draw bar, said draw bar being free to move rearwardly independently of the yoke.

6. As an article of manufacture, a yoke 110 for railway draft rigging, said yoke comprising spaced, parallel arms and a hollow box-like head uniting the forward ends thereof, the upper wall of said head being provided with a transversely extending gib 115 on its inner face adapted to coöperate with the upper shoulder of a standard draw bar butt, the lower wall of said head being spaced vertically below said gib sufficiently to permit the insertion, by longitudinal 120 movement, of the butt within the head, means associated with said head adapted to engage, under draft, the front face of the lower shoulder of the butt when the latter is in operative position, and means also associated with said head, located rearwardly of the first named means, adapted to be positioned beneath and in engagement with the lower face of the butt when the latter 125 is in operative position to thereby support 130

the butt in elevated position with the upper shoulder thereof in alinement with said gib.

7. In combination, a yoke member comprising strap portions, sides formed integrally with the forward ends of said strap portions and extending therebetween to form a hooded forward end, one of said strap portions being depressed and offset at its forward end to permit insertion therein of a coupler butt, and a key member extending through said sides and arranged to prevent withdrawal of said coupler butt from assembled position, said key member being provided with a bearing portion for said coupler butt, said portion being of thickness corresponding to the depression of said strap portion, said key member being further provided with a shoulder to coact with said coupler butt to prevent its withdrawal from said yoke, the other of said strap portions being shouldered to coact with said key member to prevent such withdrawal of said coupler butt.

8. As an article of manufacture, a railway draft rigging yoke adapted for detachable connection with a standard draw bar, said yoke comprising parallel arms united at their forward ends by a hollow box-like head, one of the walls of said head being provided with means on its inner face adapted to coöperate with one shoulder of a standard draw bar butt, the opposite wall of said head being spaced vertically from said means sufficiently to permit the insertion, by longitudinal movement, of the butt within the head, means associated with said head

adapted to engage, under draft, the front face of the opposite shoulder of the draw bar butt when the latter is in operative position and to occupy the space at the rear of 40 said last named shoulder between the adjacent horizontal face of the butt and said last named wall of the head to thereby maintain the butt in operative position with said first named means.

9. As an article of manufacture, a railway draft rigging yoke adapted for detachable connection with a standard shouldered draw bar, said yoke comprising a U-shaped loop portion and a hollow box-like head at 50 the front ends of the arms of the loop portion, the upper wall of said head being provided on its inner face with a transverse gib adapted to engage the upper shoulder of the draw bar butt under draft, the lower wall 55 of said head being spaced below said gib sufficiently to permit the insertion of the draw bar butt within the head by relative longitudinal movement, and removable means associated with said head, said means being 60 adapted to be positioned underneath the lower face of the draw bar butt to thereby support the latter in elevated coöoperative engagement with said gib, said means being supported by said head, and said lower wall 65 of the head being adapted to support the butt end of the draw bar when said means are removed.

STACY B. HASELTINE.
